INVENTOR.

John D. Martin,
BY Walter N. Haskell.

his ATTORNEY.

UNITED STATES PATENT OFFICE.

JOHN D. MARTIN, OF ROCK ISLAND, ILLINOIS.

CUE-TIP CUTTER.

1,424,506.

Specification of Letters Patent. Patented Aug. 1, 1922.

Application filed November 21, 1921. Serial No. 516,530.

To all whom it may concern:

Be it known that I, JOHN D. MARTIN, a citizen of the United States, residing at Rock Island, in the county of Rock Island 5 and State of Illinois, have invented certain new and useful Improvements in Cue-Tip Cutters, of which the following is a specification.

My invention pertains to cue-tip cutters, 10 and aims to provide a simple mechanism whereby the ends of billiard cues can be renewed, and provided with a perfectly true surface, at right angles with the axis of the cue. It consists of an instrument adapted to 15 receive the tip end of a cue, and a cutting blade by means of which a portion of the end of the cue can be shaved off, upon the cue being rotated.

In the drawings;

20 Fig. 1 is a top end view of the invention. Fig. 2 shows the same in side elevation. Fig. 3 is a lower end view thereof.

Fig. 4 is a detail of the block 7.

1 is a casing, preferably formed of sheet 25 metal, and of a modified triangular form in cross-section, to one end of which is pivoted, as at *a*, a cutter 2, having a blade 3. Fixed to the end of the casing is a plate 4 having a threaded perforation in which is operable 30 a thumb-screw 5, having a ball-and-socket connection with the cutter 2, as at *b*. The free end of the cutter is movable in a guide 6, also fixed to the end of the casing.

A block 7 is held within the casing, by 35 means of a thumb-screw 8, turning in a tapped opening in a plate 9, secured to the casing 1. The block 7 is provided with a plate 10, having a key-hole slot 11, in which is held a button (not shown) on the inner 40 end of the screw 8. On the opposite side the block 7 has an angular recess 12, between which and the curved portion 13 of the casing the end of a cue may be held, as indicated by a circle at 14.

By operation of the screw 8 the block 7 is 45 caused to embrace the end of the cue snugly, but not so tightly as to prevent the rotation thereof. When in this position, with the end of the cue against the cutter 2, such cutter is moved by the screw 5 until the edge of 50 the blade is on a line with the axis of the cue. By then giving a rotatory movement to the cue, any inequalities or uneven portions of the end thereof will be shaved off. The cutter 2 being established at a right 55 angle with the walls of the casing 1, the resulting cut made by the blade must of necessity be at right angles with the axis of the cue.

It will be noted that the adjustment of 60 the block 7 by means of the screw 8 will enable the tool to be used with cues of varying diameters, and that the adjustment feature of the cutter makes it possible to set the same for cue tips of different diameters. 65

The device is of suitable size and shape to be held in the hand of the operator, and it is specially adapted for use in billiard and pool halls, where the tips are frequently being required to be replaced and renewed. 70

What I claim, and desire to secure by Letters Patent, is:

A device of the class described, comprising a casing, open at both ends; a cutter pivoted at one end of said casing, in a plane 75 at right angles with the walls of said casing; a thumb-screw supported on the end of said casing and operatively connected with said cutter, to cause a movement thereof transversely of the end of the casing; 80 a guide for the free end of said knife, fixed on the end of said casing; a clamp-block held within said casing, so as to be movable therein, transversely of the casing; and means for transverse adjustment of said 85 block.

In testimony whereof I affix my signature.
JOHN D. MARTIN.
